UNITED STATES PATENT OFFICE.

CHARLES FROLICH, OF NEW YORK, N. Y.

ARCH CENTER BRACE.

SPECIFICATION forming part of Letters Patent No. 642,972, dated February 6, 1900.

Application filed March 20, 1899. Serial No. 709,765. (No model.)

To all whom it may concern:

Be it known that I, CHARLES FROLICH, a citizen of the United States, residing at New York, (Brooklyn,) in the county of Kings and 5 State of New York, have invented certain new and useful Improvements in Arch Center Braces, of which the following is a full and complete specification, such as will enable those skilled in the art to which it appertains 10 to make and use the same.

This invention relates to arch center braces for use in building construction; and the object thereof is to provide a device of this class which is adjustable for use in constructing 15 arches of varying span.

The invention is fully disclosed in the following specification, of which the accompanying drawings form a part, in which like figures denote like parts in the several views, 20 and in which—

Figure 1 is a side view of my device in operative position; Fig. 2, an end view of two of said devices in operative position; Fig. 3, a top view of an altered form thereof in operative position, and Fig. 4 is a side view of 25 a detail of Fig. 3.

Referring more particularly to the drawings, my arch center brace is composed of two members 5 and 5^a, which are preferably composed of planking and are placed side by side. One of said members 5^a is slotted longitudinally, as at 6, and the other member is provided with adjusting-bolts 7, which operate in the slot 6 and are provided with the usual 30 nuts and washers 8. Each of the members 5 and 5^a is grooved or recessed at the end, as at 9, to fit the flange 10 of girders 11, used in building construction, and when the members 5 and 5^a are suitably relatively adjusted 35 the brace may be supported between two of said girders, as shown in the drawings. Each of the members 5 and 5^a is provided with an arm 12, adjustably secured to the end portion thereof by means of an adjusting-bolt 13, 40 which operates through a longitudinal slot 14 in said arm. Each arm 12 is provided with a yoked outer end portion 15, and a cross-beam 16 (shown in dotted lines) may be supported by the yokes of said arms at any predetermined height. The arms 12 are so arranged

upon the members 5 and 5^a that the yokes shall support the cross-beam 16 parallel to the line of extension of the members 5 and 5^a.

If two or more of the devices constructed as described be supported parallel between 55 two girders and the cross-beam 16 be supported by the arms 12 of each, the planks 17 (shown in dotted lines) may be supported thereby between the girders 11 and the arch built up thereon. When the arch has been 60 constructed and allowed to set and harden, the center brace, cross-beams, and planks may be removed and reused in constructing arches in other portions of the building and in connection with girders at any distance 65 apart. The concrete or other arch material is also filled in between the adjacent sides of the I beams or girders 11 and between the flanges 10 thereof.

In Figs. 3 and 4 I have shown an altered 70 form of arch center-brace, in which the construction is the same as in Figs. 1 and 2, in combination with a supplemental brace member 18, which is designed to be used in connection with one of the members 5 and 5^a in 75 building arches in a corner portion of the girder structure or any portion thereof where, due to the presence of a pillar or other obstacle, the unaugmented center brace cannot be used. 8c

Supposing a pillar should be located as at 19 in Fig. 3 and it were desired to arch over the space adjacent thereto, the supplemental member 18 would be suspended from the member 5^a, and the flange 10^a of the girder 85 11^a extending at right angles to the girders 10. The supplemental member 18 is provided with a shoulder 20 for engagement of the upper portion of the member 5^a and a recess 21 for engagement of the flange 10^a and also with 90 a recess 22, in which a cross-beam similar to the cross-beam 16 may be supported. If two of such supplemental members 18 be similarly and parallelly mounted, a cross-beam may span the space between them and suitable planking be supported thereby in connection with the cross-beam supported by the adjacent arms 12 12 of the members 5 and 5^a. The supplemental member 18 is provided 95 upon each face with a fixed piece 23, which 100

operates to hold firmly a plank, which may rest upon the piece 18 and take the place of the cross-piece which is used in the recess 22.

The entire space between the girders of a building may thus be arched over and the center braces reused indefinitely.

Having fully described my invention, I claim as new and desire to secure by Letters Patent—

- 10 1. In a device of the class described, a member provided at one end with a groove, and with an adjustable arm provided at its outer end with a yoke portion, substantially as shown and described.

2. An arch center brace consisting of two 15 adjustably-connected members, each of which is provided with an upwardly-directed adjustable arm provided at its outer end with a yoke portion, substantially as shown and described.

In testimony that I claim the foregoing as 20 my invention I have signed my name, in presence of the subscribing witnesses, this 18th day of March, 1899.

CHARLES FROLICH.
